UNITED STATES PATENT OFFICE.

MINARD A. WILSON, OF IRVINGTON, NEW JERSEY.

COMBINATION-TAILPIECE FOR VIOLINS.

1,397,193.

Specification of Letters Patent.

Patented Nov. 15, 1921.

Application filed April 15, 1920. Serial No. 374,084.

To all whom it may concern:

Be it known that I, MINARD A. WILSON, a citizen of the United States, residing at Irvington, in the county of Essex and State 5 of New Jersey, have invented certain new and useful Improvements in Combination-Tailpieces for Violins, of which the following is a specification.

This invention is in the nature of an improved combination tail piece for violins, the same being composed of a circular arm, foot and tail, in one piece, so as to prevent side slipping, and forward pulling out from under the chin, resting on outer edge and ribs 15 only, the angle, curve and balance foot being the main features.

In order that the construction and operation thereof may be readily comprehended, I have illustrated an approved embodiment of 20 my invention in the accompanying drawing, and will now proceed to fully and specifically describe the same in connection with said drawing, in which—

Figure represents the rear portion of a 25 violin, in plan view, with my tail piece mounted thereon;

Fig. 2, a sectional view, on the central, vertical, longitudinal plane indicated at 2—2 in Fig. 1;

Fig. 3, a bottom plan view of the tail piece detached from the violin; and

Fig. 4, a sectional view, on the transverse vertical plane indicated at 4—4 in Fig. 2.

Like reference characters mark the same 35 parts in all of the figures of the drawing.

Referring specifically to the drawing, 5 indicates the belly, 6, the back, and 7 the rear end of a violin of any ordinary construction, upon which is mounted a bridge 8, also of 40 the usual construction.

My improved combination tail piece consists of a main body, 9, from which projects a short rear arm 10 on one side and a curved arm 11 on the opposite side, and as these 45 parts are arranged, I provide a pin 12, with its grain at right angles to that of the body 9 and arms 10 and 11, which I insert transversely through the two wings and the rear portion of the body, to give strength and 50 stiffness to the arms.

The arm 11 curves forward at its outer end 13, and slightly inward at its top.

The tail piece is provided, in its under side with a recess 14 in which is mounted a metal 55 plate 15, having two openings which

coincide with two openings extending thence through the rear end of the body, a suitable wire loop 16 being provided, whose arms pass through the openings in the body and the metal plate and are suitably twisted or otherwise secured together in the recess 14, while the loop proper projects beyond the rear end of the tail piece and engages over a suitable screw 17 secured in and projecting beyond the rear end 7 of the violin.

The rear end of the tail piece rests solely on ribs 18 provided at the outer edge of the under surface of the arms thereof, these ribs being the sole contact with the violin so that the tone thereof is not muted.

The strings 19 of the violin, after passing over the bridge 8, pass over a rib 20 formed across the top of the forward end of the body 9, and thence downward, through openings 21 in said body, being suitably knotted, 75 as at 22, or otherwise secured.

The ribs 18 prevent the tail piece from side slipping or forward pulling out from under the chin, which is a great relief to the muscles of the neck.

The chin lays rather over the circular or curved arm, than on it, and the violin well under the chin and on the collar bone, which is the proper position to give the greatest command of the instrument.

The angles, curve and balance feet are the main features, and no bolts, screws, or bands are used.

The wire as a retainer, serves to keep the tone up better and longer than the "gut" 90 string in general use and it holds its position at any angle to which the bridge may be cut.

Other virtues and advantages will be observed in the use of this invention and slight 95 changes and variations may be made in the construction of the various parts without departing from the spirit and scope of the invention.

Having thus fully described my invention, 100 what I claim as new and desire to secure by Letters Patent of the United States is:

1. A combination tail piece for violins provided with a main body, and two laterally projecting arms at the rear end thereof, 105 said arms having bottom ribs at their rear edges, extending transversely of the body to form the sole supporting contact with the violin.

2. A combination tail piece for violins 110

comprising a main body and two arms projecting laterally at its rear end, one of said arms being short and at right angles to the body, and the other longer and curved forwardly and inwardly at its end.

3. A combination tail piece for violins comprising a main body and two arms projecting laterally at its rear end, one of said arms being short and at right angles to the body, and the other longer and curved forwardly and inwardly at its end, and said arms being provided at their rear under edges with downwardly projecting ribs forming the sole points of contact with the violin.

4. A combination tail piece for violins provided with a main body, and two laterally projecting arms at the rear end thereof,

said arms having bottom ribs at their rear edges, extending transversely of the body to 20 form the sole supporting contact with the violin, means in the form of a transverse rod being inserted in the arms and body to stiffen and strengthen the structure.

5. A combination tail piece for violins 25 comprising a main body and suitable lateral arms, the main body being recessed in its under surface, and two openings being made from said recess out through the rear end of the body, a metal plate in the recesss having openings coinciding with the openings in the body, and a wire loop having its arms 30 passing through said openings and secured in the recess.

In testimony whereof I affix my signature. 35
MINARD A. WILSON.
